UNITED STATES PATENT OFFICE.

MARVIN A. HAGEY AND LOREN T. MCKEE, OF LOS ANGELES, CALIFORNIA.

AUTOMATIC WATER CONTROL.

Application filed September 21, 1925. Serial No. 57,724.

To all whom it may concern:

Be it known that we, MARVIN A. HAGEY and LOREN T. MCKEE, citizens of the United States, and residents of Los Angeles, in the county of Los Angeles and State of California, have invented new and useful Improvements in Automatic Water Controls, of which the following is a specification.

This invention relates to a hydraulically actuated device for automatically and intermittently operating mechanisms such as flush valves. It is especially serviceable in connection with flushing devices for toilets and urinals wherein it is desired to effect an intermittent flush.

It is the primary object of this invention to provide a mechanism which comprises a reciprocating motor element wherein an operating member is slowly moved toward the outer end of its stroke by the flow of fluid into its chamber; and, at the outer end of its stroke, a relief is actuated to cause discharge of fluid from the chamber, whereupon the cycle is repeated. In addition to the broader objects of this invention there are certain details of design, whereby an economical, simple, durable and compact structure is obtained.

These objects together with other objects and corresponding accomplishments are obtained by means of the embodiment of our invention illustrated in the accompanying drawings in which:

Fig. 1 is a section through a flush valve having our improved operating mechanism connected thereto; and Fig. 2 is a section as seen on the line 2-2 of Fig. 1.

Referring more particularly to the drawings, the body of a flush valve commonly known as a flushometer is indicated by 3. The body is provided with an inlet chamber 4 from which extends an inlet 5 adapted to be connected to the supply service pipes. The upper portion of the body has a cylindrical rim 6 which is externally threaded, and is provided with a passage or duct 7 leading upwardly through the wall. At the opposite side is an extension 8 having a passage or duct 9 leading therethrough. The passage 9 extends upwardly through the wall of the rim 6 and at the extension 8 is provided with a check valve 10 for controlling the flow. Upstanding in the body at the central portion thereof is a tubular seat 11 communicating with a discharge outlet 12 adapted to be connected to piping leading to the device to be flushed. The body is so arranged that liquid may enter the inlet side and in order to pass outwardly must pass over the upper portion of the tubular seat 11 and downwardly through the outlet 12.

Mounted on the rim 6 and secured thereto by threads is a cap 13 having a flange 14 arranged to cooperate with the upper portion of rim 6 and clamp therebetween a flexible diaphragm 15 preferably formed of rubber. The diaphragm has a port 16 at the center thereof which registers with the port in the tubular seat 11. There is an annular passage 17 in the cap communicating with the space above the diaphragm through ports 18 arranged to register with the ducts 7 and 9 so that there is a duct placing the portion of the structure above the diaphragm in communication with the portion below the diaphragm, the duct being small. Likewise the duct 9 communicates with the space above the diaphragm. Secured to the diaphragm at the port therein is a tubular member 19, there being sufficient clearance between the internal wall of the tubular port and the member 19 to permit the flow of water therebetween. In order to guide the tube the tube 19, there are fins 20 provided. The upper end of tube 19 serves as a seat for a valve disc 21 having a stem 22 depending therefrom and extending below the bottom of tube 19. This structure provides a tilting valve. Formed on the side of the body is an extension 23 in which is slidably mounted a stem 24 arranged to be registered with the stem 22. There is a compression spring 25 surrounding the stem 24 and arranged to engage a head 26 thereby tending to hold the stem 24 in its outer position and away from stem 22. Upon pressing the head 26, the stem 24 will be caused to engage the stem 22 and tilt the valve disc 21 on its seat, thereby lifting the latter. The structure just described is well known in the art and forms no part of our present invention.

Our invention relates to the means for tilting the stem 22. Secured to the extension 23 is a cylindrical housing 27 having a head 28 provided with a discharge chamber 29. The discharge chamber is connected by a tube 30 to extension 8 so as to communicate with duct 9. An inlet is provided in the head 28 and a tube 31 connected thereto. A fitting 32 connects tube 31 and a tube 33

which leads to the inlet 5 of the flush valve. Fitting 32 contains a needle valve 34 for controlling the flow of liquid in the tubes 33 and 31 to the head. Mounted within the housing 27 and secured to the head is a sylphon 35 arranged so that when it is expanded it will engage the head 26 and move stem 24. In retracted position or when collapsed which is the normal position of the sylphon, the latter is out of engagement with head 26 and the stem is permitted to remain in position such that the valve disc 21 may seat.

The device operates in the following manner: Water enters the valve through inlet 5 and passes upwardly through duct 7 and passage 17 to the space above diaphragm 15. While disc 21 is seated, the liquid is within a closed relief chamber, forcing diaphragm 15 downwardly so that it seats upon tubular seat 11 and closes the passage for water to the outlet. Water from the inlet also passes through tube 33, past valve 34 and through tube 31 to the sylphon. The escape of water from the sylphon is prevented, as tube 30 communicates with the relief chamber above diaphragm 15. The sylphon is then caused to expand, eventually engaging the head 26 and stem 24 and moving the latter inwardly. Stem 24 engages stem 22 and unseats the valve 21, opening the relief chamber to the discharge. Water then discharges from the relief chamber, and the pressure of the water below diaphragm 15 causes the latter to raise from seat 11 and open the inlet 5 to the discharge outlet 12, permitting the free passage of water. Upon the relief chamber being open to the discharge, the sylphon is relieved of its pressure, being in communication therewith, and immediately contracts allowing stem 24 to be retracted. Valve 21 then rights itself and seats. Water begins to slowly enter the relief chamber through duct 7 and passage 17, moving the diaphragm 15 downwardly until it eventually seats on tubular seat 11 and closes the discharge ports stopping the flow of water. The outflow of water from the sylphon is also stopped, and water enters the latter from the inlet through tubes 33 and 31,

again expanding the sylphon and eventually tripping the relief valve, whereupon the operation is again performed.

Our invention resides in the tripping mechanism, which may be applied to any flush valve or to other devices. The sylphon and associated parts form a device herein-after broadly referred to as a motor.

What we claim is:

1. A device of the character described adapted to be connected to a hydraulically actuated flush valve having a relief chamber and mechanically operated means to release fluid therefrom so as to operate said valve including a slidable actuating stem, said device comprising an expansible chamber motor, a fluid inlet for said motor connected to the inlet of said valve and arranged to permit the passage of fluid slowly to said motor, said motor having a fluid outlet connected to said relief chamber, said stem being disposed to be engaged and operated at an end of the travel of the motor.

2. A device of the character described comprising a sylphon motor having a fluid inlet connected to a source of fluid supply under pressure, a needle valve arranged to control the passage of fluid through said inlet, said motor having a fluid outlet, relief means for said outlet including an actuating stem, a check valve for preventing the back flow of liquid through said outlet, said stem being disposed in the path of travel of said motor so as to be operated thereby.

3. The combination with a flush valve having a relief chamber, a relief tilting valve and a slidale stem for actuating said valve of a control device comprising an expansible chamber motor having a constricted fluid inlet connected to the source of fluid supply under pressure arranged to permit the passage of fluid slowly, said motor being provided with a fluid outlet connected to said relief chamber, said stem being disposed to be engaged and operated by the motor at the end of its travel.

In witness that we claim the foregoing we have hereunto subscribed our names this 9th day of September, 1925.

LOREN T. MCKEE.
MARVIN A. HAGEY.
